UNITED STATES PATENT OFFICE.

CHARLES S. WEBER, OF CLEVELAND, OHIO.

STRINGING PIANOS.

SPECIFICATION forming part of Letters Patent No. 361,384, dated April 19, 1887.

Application filed April 8, 1885. Serial No. 161,599. (No model.)

To all whom it may concern:

Be it known that I, CHARLES S. WEBER, a naturalized citizen of the United States, residing at Cleveland, in the county of Cuyahoga and State of Ohio, have invented certain new and useful Improvements in Stringing Pianos; and I do declare the following to be a full, clear, and exact description of the invention, such as will enable others skilled in the art to 5 which it appertains to make and use the same, reference being had to the accompanying drawings, and to the letters and figures of reference marked thereon, which form a part of this specification, in which—

15 Figure 1 is a sectional view of the invention, in which view the reflector is removed. Fig. 2 is a plan view. Fig. 3 is a plan view showing the reflector in place. Fig. 4 is a sectional view of the construction shown in Fig. 3, and 20 Fig. 5 shows the improvement with a single bridge and with the reflector removed.

Referring to the drawings, A is the primary string, B the secondary string, D the reflector, d projections on the reflector, E is the divisor, 25 and e the rubber point of the latter, all of which will be described.

The object of the invention is to increase the volume and duration of sound obtained from the usual strings, especially in the upper or 30 so-called "treble" notes of pianos. To this end I have invented the multiplex system of stringing these instruments. Besides the usual or principal strings of a piano-forte, this system employs additional or secondary strings, which 35 are preferably a sympathetic continuation of the main string, and only separated from the same by the bridge; but such secondary stringing is employed in this system only under the following conditions: First, a secondary 40 string in no instance to receive the direct blow of the hammer; second, the sound produced by the secondary string to be like that produced by the primary one, there being no movable attachment in connection with these 45 strings to change their tone to a higher or lower octave at the will of the performer; and third, continued strings to be at least equal in length to or a multiple of the main string. By exacting in every instance each of these three 50 essential conditions the multiplex system fully

distinguishes itself from others where secondary strings have been employed.

In order to more clearly explain the nature of this system I will in the following assume the length of the main string invariably as the 55 unit. Besides, I will accept the tension of the secondary string to be equal to that of the main string. Accordingly, if I make the length of the secondary string equal to that of the main or primary string it will vibrate in 60 unison with the main string whenever this is excited by the blow of the hammer, as is done in a piano-forte. If I now give the secondary string two unit lengths it will form two equal (so-called "ventral") segments, each of 65 these vibrating in unison with the main string, and as long as the secondary string contains an even number of units or is a multiple of the main string it will form as many segments as there are units contained in the length of 70 the secondary string, and each segment will vibrate in unison with the main string whenever the latter is excited, thus increasing and enriching its tone. This law already indicates (what experiments have confirmed) that it 75 will be advantageous to have the secondary strings contain as many units as possible. As I only begin to employ these strings about the middle of a piano, where the main string takes up half the available length for string- 80 ing, it is evident that to a continued string I cannot give here more than an equal length; but as I ascend the scale, and as the main string occupies a smaller fraction of the instrument's length, I am enabled to gradually 85 increase the proportional length of the secondary string until at the highest notes, even in a piano of ordinary length, this string contains twenty or more segments, each equal in length to the principal, and each vibrating by sympathetic unison with the same. Here the additional gain in richness and quality of tone, 90 as well as in duration of sound, is such as cannot be approached by any other known method of stringing.

To further increase the brilliancy of sound obtained, I have invented an accessory appliance which I call the "reflector." This is a bar running parallel and very close to the bridge without, however, touching it. This 95

bar is firmly fastened to the frame or iron plate of the piano, and is provided with as many projections as the corresponding bridge bears pins, each string being held in position 5 by passing between a pin in the bridge and a projection of the reflector, instead of passing between two pins in the bridge, as is the case in the ordinary construction.

Two holes in the reflector might be substituted for the projections without, however, a material advantage. A reflector may be employed with the main as well as the secondary bridge; besides, it may be placed in front or behind any bridge. If placed before the main 15 bridge, the notes of the instrument so constructed will be very long, but rather subdued. Placed after the bridge, loud but somewhat shorter notes will result. In connection with the secondary bridge a reflector only can be 20 placed before the same to produce its advantageous effect, especially in instruments constructed without the reflector, and in particular where the secondary string is of great length. Besides the short waves spoken of, I 25 obtain a long one, corresponding to the whole length of the secondary string, and consequently sounding its prime tone. Though only faintly audible, this forms an unwelcome undertone to the note of the main string. To 30 suppress this long wave without interfering with the short ones, I have invented the divisor or clamp. This is a set of two small pieces of rubber, each piece having a convex side. They are securely fixed at the first or 35 last nodal point formed by the short waves. They touch the string with their convex side and hold it like a pair of tweezers, not permitting the long wave to be formed, while the short waves (only touched at their nodal points) 40 will in no way be interfered with.

As the nodal lines are intended to be inva-

riable for every string, it is obvious that the divisor must receive some firm support, which again should be well fastened on the frame-work of the piano.

45

In the foregoing I have assumed the tension equal in both sets of strings; but it is obvious that, according to a well-known physical law, I may, when necessary, correct a variation in tension by a corresponding variation 50 in length. Lastly, it may be mentioned that, as it appears advantageous to employ two bridges in connection with these instruments, I have not specially mentioned those having only one bridge, although in cases where parallel 55 strings are not employed the construction, with one bridge only, may be employed, and yet be a great improvement over such instruments where no kind of multiplicators are employed.

Having thus described my invention, what 60 I claim as new, and desire to secure by Letters Patent, is—

1. In a musical instrument, a string divided by the bridge into primary and secondary strings, the secondary string being a multiple 65 of the primary string and extended to the rear of the bridge, substantially as and for the purposes set forth.

2. The combination, with a secondary string, forming a prolongation of the prime string 70 and of a multiple length thereof, of a divisor or clamp located at a nodal point of the secondary string, to prevent a whole wave tone of the secondary string without interfering with the short wave tones, substantially as and for 75 the purpose specified.

In testimony whereof I affix my signature in presence of two witnesses.

CHARLES S. WEBER.
